FIG. 4 is a left side view of a light fixture, according to the first embodiment;

FIG. 5 is a right side view of a light fixture, according to the first embodiment;

FIG. 6 is a top view of a light fixture, according to the first embodiment;

FIG. 7 is a bottom view of a light fixture, according to the first embodiment;

FIG. 8 is a front, bottom perspective view of a light fixture, according to a second embodiment;

FIG. 9 is a front, top perspective view of a light fixture, according to the second embodiment;

FIG. 10 is a front side view of a light fixture, according to the second embodiment;

FIG. 11 is a left side view of a light fixture, according to the second embodiment;

FIG. 12 is a right side view of a light fixture, according to the second embodiment;

FIG. 13 is a top view of a light fixture, according to the second embodiment;

FIG. 14 is a bottom view of a light fixture, according to the second embodiment;

FIG. 15 is a front, bottom perspective view of a light fixture, according to a third embodiment;

FIG. 16 is a front, top perspective view of a light fixture, according to the third embodiment;

FIG. 17 is a front side view of a light fixture, according to the third embodiment;

FIG. 18 is a left side view of a light fixture, according to the third embodiment;

FIG. 19 is a right side view of a light fixture, according to the third embodiment;

FIG. 20 is a top view of a light fixture, according to the third embodiment;

FIG. 21 is a bottom view of a light fixture, according to the third embodiment;

FIG. 22 is a front, bottom perspective view of a light fixture, according to a fourth embodiment;

FIG. 23 is a front, top perspective view of a light fixture, according to the fourth embodiment;
 FIG. 24 is a front side view of a light fixture, according to the fourth embodiment;
 FIG. 25 is a left side view of a light fixture, according to the fourth embodiment;
 FIG. 26 is a right side view of a light fixture, according to the fourth embodiment;
 FIG. 27 is a top view of a light fixture, according to the fourth embodiment;
 FIG. 28 is a bottom view of a light fixture, according to the fourth embodiment;
 FIG. 29 is a front, bottom perspective view of a light fixture, according to a fifth embodiment;
 FIG. 30 is a front, top perspective view of a light fixture, according to the fifth embodiment;
 FIG. 31 is a front side view of a light fixture, according to the fifth embodiment;
 FIG. 32 is a left side view of a light fixture, according to the fifth embodiment;
 FIG. 33 is a right side view of a light fixture, according to the fifth embodiment;
 FIG. 34 is a top view of a light fixture, according to the fifth embodiment;
 FIG. 35 is a bottom view of a light fixture, according to the fifth embodiment;
 FIG. 36 is a front, bottom perspective view of a light fixture, according to a sixth embodiment;
 FIG. 37 is a front, top perspective view of a light fixture, according to the sixth embodiment;
 FIG. 38 is a front side view of a light fixture, according to the sixth embodiment;
 FIG. 39 is a left side view of a light fixture, according to the sixth embodiment;
 FIG. 40 is a right side view of a light fixture, according to the sixth embodiment;
 FIG. 41 is a top view of a light fixture, according to the sixth embodiment;
 FIG. 42 is a bottom view of a light fixture, according to the sixth embodiment;
 FIG. 43 is a front, bottom perspective view of a light fixture, according to a seventh embodiment;
 FIG. 44 is a front, top perspective view of a light fixture, according to the seventh embodiment;
 FIG. 45 is a front side view of a light fixture, according to the seventh embodiment;
 FIG. 46 is a left side view of a light fixture, according to the seventh embodiment;
 FIG. 47 is a right side view of a light fixture, according to the seventh embodiment;
 FIG. 48 is a top view of a light fixture, according to the seventh embodiment;
 FIG. 49 is a bottom view of a light fixture, according to the seventh embodiment;
 FIG. 50 is a front, top perspective view of a light fixture, according to an eighth embodiment;
 FIG. 51 is a front, bottom perspective view of a light fixture, according to the eighth embodiment;
 FIG. 52 is a front side view of a light fixture, according to the eighth embodiment;
 FIG. 53 is a left side view of a light fixture, according to the eighth embodiment;

FIG. 54 is a right side view of a light fixture, according to the eighth embodiment;
 FIG. 55 is a top view of a light fixture, according to the eighth embodiment;
 FIG. 56 is a bottom view of a light fixture, according to the eighth embodiment;
 FIG. 57 is a front, bottom perspective view of a light fixture, according to a ninth embodiment;
 FIG. 58 is a front, top perspective view of a light fixture, according to the ninth embodiment;
 FIG. 59 is a front side view of a light fixture, according to the ninth embodiment;
 FIG. 60 is a left side view of a light fixture, according to the ninth embodiment;
 FIG. 61 is a right side view of a light fixture, according to the ninth embodiment;
 FIG. 62 is a top view of a light fixture, according to the ninth embodiment; and,
 FIG. 63 is a bottom view of a light fixture, according to the ninth embodiment.
